UNITED STATES PATENT OFFICE.

CHARLES P. STEINMETZ, OF SCHENECTADY, NEW YORK, ASSIGNOR TO GENERAL ELECTRIC COMPANY, A CORPORATION OF NEW YORK.

CONSTANT-CURRENT RECTIFIER SYSTEM.

1,131,282.

Specification of Letters Patent.

Patented Mar. 9, 1915.

Application filed May 23, 1905. Serial No. 261,868.

To all whom it may concern:

Be it known that I, CHARLES P. STEINMETZ, a citizen of the United States, residing at Schenectady, county of Schenectady, State of New York, have invented certain new and useful Improvements in Constant-Current Rectifier Systems, of which the following is a specification.

This invention relates to a system of electrical distribution in which alternating current is rectified to produce a unidirectional current applicable to series circuits requiring substantially constant current.

The invention also relates to the forms of apparatus whereby this result is obtained.

In carrying out my invention I make use of the peculiar property of a mercury or similar arc, whereby current is permitted to pass freely through the arc in one direction but is prevented from flowing in the opposite direction.

The details of my invention will be better understood by reference to the following description taken in connection with the drawings forming part of this specification.

Figure 1 is a diagram representing my improved system of electrical distribution; Figs. 2 and 3 are explanatory diagrams; Fig. 4 comprises a group of curves showing various relations between electro-motive forces and the current in different parts of the system; and Fig. 5 shows a modified form of reactance device for supplying current to the auxiliary anodes.

Referring to Fig. 1, the mercury rectifier 1 is connected through a transformer 2 to the source of constant potential 3. This transformer 2 is in some respects similar to the ordinary tub transformer for converting constant potential alternating current into constant current, but differs in some particulars, which are hereinafter pointed out. The transformer comprises a primary coil 4 and a floating secondary coil 5, the terminals 6 and 7 of which are connected, respectively, to the anodes 8 and 9 of the mercury rectifier through reactance devices 10 and 11. The mercury cathode 12 of the rectifier is connected through a reactance 13 to a series circuit containing a plurality of translating devices 14, such for instance, as mercury lamps, magnetite or other arc lamps. The other end of this consumption circuit is connected to a tap 15 from the center of

the secondary 5. The rectifier is also provided with two auxiliary electrodes 16 and 17 separated from the cathode 12, but located near enough thereto so that when the rectifier is shaken or tipped slightly, a small quantity of mercury will flow from these auxiliary electrodes to the cathode or vice versa, to establish a starting arc in the lower end of the rectifier for the purpose herein-after pointed out. These electrodes 16 and 17 are supplied with current from the low potential secondary 18 of a transformer, the primary 19 of which is connected to the constant potential source 3. A reactance device 20 is connected directly across the terminals of the secondary 18 and is provided with a tap 21 from which a conductor leads to a reactance 22 and then to the cathode 12. These auxiliary anodes 16 and 17, together with their correlating transformer and reactances, operate to render the space within the rectifier conductive for current from the transformer secondary 5 in a manner hereinafter described more in detail.

The operation of the mercury arc rectifier is based on the phenomenon of the electric arc by virtue of which current is conducted through the arc in one direction but is prevented from flowing freely in the opposite direction, so as to pass only unidirectional currents. In an electric arc, current is carried across the gap between the terminals by a bridge of conducting vapor consisting of material, projected and constantly replenished by a high velocity blast issuing from the cathode. The arc, therefore, must be continuous at the cathode, though it may be shifted from anode to anode. Any interruption of the cathode blast puts out the arc by interrupting the supply of conducting vapor. With an alternating impressed E. M. F. the arc, if established, will go out at the end of the half-wave, or if a cathode blast is maintained continuously by a second arc, only alternate half-waves can pass, namely, those for which that terminal is negative from which the continuous blast issues. The arc, with an alternating impressed voltage, consequently rectifies the current, and the voltage range of rectification is very great.

In Fig. 2 is shown diagrammatically a constant-current transformer having a primary 23 and a secondary having its terminals 24 and 25 connected respectively to the

anodes 26 and 27 of a mercury rectifier. The cathode 28 of the rectifier is connected through a series circuit 29 to a tap 30 in the center of the transformer secondary. With 5 such an arrangement, an alternating current in the primary 23 will impress a voltage between the secondary terminals 24 and 25 having the wave form shown in curve I of Fig. 4. The voltages from 30 to 24 and 10 from 30 to 25 are given by curves II and III. If now, 24, 25 and 30 are connected with the corresponding rectifier terminals 26, 27 and 28, and at 28 a cathode blast is maintained, those currents will pass for which 28 is negative or cathode, that is, the current flowing 15 through the rectifier from 26 to 28 and from 27 to 28 under the impressed E. M. F.'s II and III, give curves IV and V, and the current issuing from 28 will be the sum of IV and V, as shown in curve VI. Such a rectifier would, however, not be self-exciting, but would require some outside means for maintaining the cathode blast at 28, for the current in the first half-wave 31 in curve VI 20 goes down to zero at the zero value of E. M. F. III, before the current of the next half-wave 32 is started by the E. M. F. II. It is therefore necessary to maintain the current of the first half-wave 31 beyond the 25 zero value of its propelling impressed electro-motive force III until the current of the next half-wave 32 has started, that is, to overlap the currents of the successive half-waves. This is done by inserting reactances 30 33 and 34 into the leads from the transformer, as shown in Fig. 3. The effect of these reactances is that the current of the first half-wave 31 of curve VI continues to flow beyond the zero of its impressed 35 E. M. F. III or, in other words, until the E. M. F. III has died out and reversed and the current of the next half-wave of curve VI has been started by the E. M. F. II. Thus the two half-waves 31 and 32 of the current 40 overlap and each half-wave lasts for more than half a period or for more than 180°. The current waves resulting are shown in curve VII. The current half-wave 31 starts at the zero value of its E. M. F. III but rises 45 slower than it would without reactance, following essentially the exponential curve of a starting current, and the energy which is so consumed by the reactance as counter E. M. F., is returned by maintaining the 50 current half-wave beyond the E. M. F. wave, that is, beyond 180°. By this means a rectifier becomes self-exciting, as each half-wave by over-lapping with the next, maintains the cathode blast until the next half-wave is 55 started. The successive current half-waves added give the rectified or unidirectional curve VIII. Although I have shown separate reactances 10 and 11 in the anode leads, it will be understood that if desired the necessary reactive effect may be produced by 60

the transformer secondary itself when suitably designed; or as an alternative construction, the transformer secondary may contain slightly less reactance than is necessary to produce proper overlapping of the current 70 waves and small reactances may be introduced in the leads to make up the balance, thus allowing a certain flexibility of adjustment in the system. During a certain portion of time in each half-wave, from the zero 75 value of E. M. F., arcs flow simultaneously between 26 and 28 and between 27 and 28. During the existence of both arcs there can be no potential difference between the rectifier terminals 26 and 27, and the impressed 80 E. M. F. between the rectifier terminals 26 and 27 therefore has the form shown in curve IX, that is, remains zero for X degrees and then, with the breaking of the arc of the preceding half-wave jumps up 85 to its normal value. The induced E. M. F. of the transformer secondary must, however, more or less completely follow the primary impressed E. M. F. wave or, in other words, have the general shape shown in curve I, 90 and consequently the difference between IX and I must be taken up by the reactance. That is, during the time when both arcs flow in the rectifier, the reactive coils 33 and 34 consume the induced E. M. F. of the transformer secondary, and the voltage across these reactive coils is, therefore, as shown in curve X. Thus the reactive coil consumes voltage at the start of the current of each half-wave, at 35 in curve X, and produces 100 voltage near the end of the current flow, at 36. Between this time the reactive coil has practically no effect and its voltage is low, corresponding to the variation of the rectified alternating current, as shown in curve 105 XI. Thus during this intermediary time the alternating reactive coils merely assist the direct current reactive coil 37. Since the voltage at the alternating terminals of the rectifier 26 and 27 has two periods of zero 110 value during each cycle, the rectified voltage between 28 and 30 must also have the same zero periods and is indeed the same curve as IX, but reversed as shown in curve XII. Such an E. M. F. wave cannot operate arcs, 115 especially mercury arcs, since during the zero period of voltage the arcs go out. The voltage on the direct current line must never fall below the counter E. M. F. of the arcs and since the resistance of this circuit is low, 120 about 10%, it follows that the total variation of direct current line voltage must be below 10%, that is, the voltage practically constant, as shown in dotted lines in curve XII. To overcome this difficulty a high reactance 37 is inserted into the direct current circuit which consumes the excess voltage during that part of curve XII where the rectified voltage is above line voltage, and supplies the line voltage during the period 125 130

of zero rectified voltage. The voltage across this reactive coil, therefore, is as shown by curve XIII.

Referring now to Fig. 1, it will be noted that the reactances 10 and 11 correspond respectively to the reactances 33 and 34 of Fig. 3, the functions of which have been set forth in detail in the preceding discussion. Similarly, the reactance 13 of Fig. 1 corresponds in function to the reactance 37 of Fig. 3. In addition to these features Fig. 1 shows one means contemplated by me for starting the first discharge through the mercury rectifier. This starting means comprises the two auxiliary electrodes 16 and 17 which are supplied with current from the secondary 18 of a transformer, and comprises also an arrangement of reactance devices 20, 22, whereby these two auxiliary electrodes 16 and 17 may alternately pass current to the main cathode 12, and furthermore may maintain an overlapping phase relation of these successive current waves so that the cathode 12 is at all times energized or excited by current from these auxiliary electrodes. After the rectifier has once been started the auxiliary electrodes may be cut out of circuit entirely and the rectifier will maintain itself in a conductive condition because of the effect produced by the reactances 10 and 11 in the manner previously discussed, but on the other hand, the continuous use of the auxiliary electrodes 16 and 17 requires the expenditure of only a small quantity of energy and has the advantage that if the consumption circuit is accidentally opened or is subjected to marked fluctuations from any cause the auxiliary exciting means serves to bridge over these disturbances and prevents the rectifier from being extinguished.

By the construction above described the circuit which supplies current to the auxiliary anodes is effectively insulated from the constant potential source 3, so that there is no danger of introducing the high potential arc current into the constant potential circuits.

When desired, I may combine the reactance and transformer as in the apparatus shown in Fig. 5, which consists of a primary coil 19' adapted for connection to the constant potential source 3 and wound in two sections on the two legs of an iron core 20' having a magnetic shunt 20''. A second coil 18' is wound in two sections on this core and is provided with a tap from which a circuit may be completed through the reactance 22' to the rectifier cathode 12. The terminals of this coil 18' may be connected respectively to the starting electrodes 16 and 17. The magnetic shunt 20'' extends into proximity to the respective end pieces of the rectangular core, and its ends lie respectively between the sections of the pri-

mary coil and between the sections of the secondary coil. By this arrangement leakage paths of low reluctance are afforded for the primary and secondary fluxes. The leakage path for the alternating primary flux, including as it does the wide air gaps on either side of the shunt 20'', is of greater reluctance than the local leakage paths for the individual secondary coils. It may be noted that due to the action of the rectifier fed by the secondary coils, current flows alternately in said coils and is unidirectional in each. The leakage path for each secondary coil is thus across the adjacent corner of the shunt 20'' and so includes a wide air-gap between the end of the shunt 20'' and the main coil.

Although I have described an apparatus for starting a rectifier tube from an alternating current circuit it should be understood that I may also start it by the use of a storage battery connected between one of the auxiliary electrodes and the cathode, or I may if desired start the tube by tilting it so that the mercury in the cathode cup flows the entire length of the anode chamber and draws an arc from one of the anodes when the tube is restored to its original position. Such a method of starting is particularly applicable to the construction of tube shown in Fig. 3.

The rectifier itself embodies certain features which I consider of importance. As the conditions for successful operation to produce constant current are somewhat different from those which exist when the rectifier is operated on constant potential circuits, I find it advantageous to inclose each of the anodes 8 and 9 in a separate tube. I also find it advantageous to use as a cathode an amalgam of a refractory metal such, for instance, as gold or silver. Such a refractory metal has no appreciable vapor tension at the temperature of the mercury arc, and so does not take part in the conduction of current between the electrodes. The presence of such a metal reduces the vapor tension of the mercury and so makes the rectifier run cooler and thereby renders the rectifying arc less liable to "strike back". By the expression "strike back" I mean the action which takes place when a mercury arc reverses so that a carbon electrode becomes momentarily a cathode. Such an action produces a short circuit through the rectifier between carbon electrodes and by the disintegration of the carbon is likely to ruin the tube.

I find it desirable to use a higher magnetic density in the transformer than is ordinarily employed in constant current transformers of the tub type, and furthermore I find it desirable to so adjust the angular relation between the weight supporting arc 38 and the lever arm 39 that the

transformer will deliver from its secondary a current which tends to decrease slightly in quantity as the voltage across the consumption circuit decreases. This adjustment is rendered desirable because of the fact that the overlapping of the current curves caused by the reactances 10 and 11 increases with a decrease of load and tends to make the rectified current increase when 10 the number of translating devices in the series circuit decreases. This adjustment of the transformer may be easily effected by shifting the weight supporting arc 38 about a pivoted connection 40 in the manner well 15 known to persons skilled in the art. An exact compounding may thus be effected so that the current through the translating devices is substantially constant under all conditions of load.

20 The specific form of mercury rectifier shown in Fig. 1 is well adapted for use on high potential circuits, as it will readily stand a pressure of many thousand volts between anodes without causing an arc to 25 strike between them. Each anode is carried in the top of a comparatively narrow chamber which is separated by a considerable distance from the mercury cathode and furthermore is shielded from the direct cathode 30 blast by a bend in the walls of the chamber as clearly shown in Fig. 1. By making these chambers small a relatively high temperature is produced in and around the anodes, thus preventing the condensation of 35 mercury at these points and so decreasing the liability of arcing between anodes. A mercury condensation chamber 41 is located directly above the mercury cathode 12 and serves to receive the direct cathode blast 40 and to relieve the anode chambers of excessive mercury vapor pressure. This condensing chamber 41 is connected to the main body of the tube through a constricted opening or neck, but I make no claim to that 45 feature herein as the same is the invention of and is described and claimed in the application of Joseph L. R. Hayden, Serial No. 284,333, filed Oct. 25, 1905.

What I claim as new and desire to secure 50 by Letters Patent of the United States, is:—

1. In a system of electrical distribution, the combination of a source of constant potential alternating current, a transformer connected thereto and adapted to deliver 55 current of varying potential from its secondary, a single phase vapor rectifier connected to said transformer secondary, reactances for maintaining said rectifier conductive for currents of one direction, a series 60 circuit containing a plurality of translating devices, a reactance in series with said devices, and means for passing current from said rectifier through said last named reactance and said translating devices.

65 2. The combination of a vapor rectifier, a

high voltage constant current source for supplying current thereto, a constant potential alternating current circuit and means connected to said circuit for rendering said rectifier conductive for current from said 70 transformer.

3. The combination of a constant potential circuit, a constant current transformer connected thereto, a rectifier tube supplied by current from said transformer, and 75 means for exciting said rectifier tube by energy from said constant potential circuit.

4. A vapor rectifier having a mercury cathode and a plurality of anodes, means for supplying alternating current to said 80 anodes and for maintaining the supply substantially constant, supplemental anodes, and means for supplying alternating current at constant potential to said supplemental anodes to render the rectifier conductive. 85

5. The combination of a transformer having relatively movable coils, a source of constant potential for supplying current to one of said coils, a vapor rectifier connected 90 to the other of said coils, a tap at or near the center of said last named coil, a constant current series circuit connected between said tap and said vapor rectifier and a reactance device in said circuit. 95

6. The combination of a transformer having relatively movable coils, a source of constant potential connected to one of said coils, a vapor rectifier connected to the other of said coils, a tap at or near the center of 100 said last named coil, a constant current circuit connected between said tap and said rectifier, and inductive devices for maintaining said rectifier conductive for current from said source. 105

7. The combination of a constant current transformer having a suitable winding, means for supplying energy to said transformer from a source of constant potential, a vapor rectifier connected to the terminals 110 of said winding, a tap from an intermediate point of said winding, a series consumption circuit connected between said tap and said rectifier, and a constant potential circuit for supplying current to said rectifier to render 115 it conductive for current from said transformer.

8. The combination of a single phase vapor rectifier having a cathode and a plurality of anodes, a consumption circuit connected to said cathode, translating devices in said circuit having an appreciable counter electro-motive force, reactive devices in circuit with said anodes to cause an overlapping of the current waves delivered to the 125 rectifier, and reactive means in the consumption circuit to prevent the fluctuations of voltage therein from falling below the counter electromotive force of said translating devices. 130

9. The combination with an alternating current circuit, and a current-rectifying device, of a transformer interposed between the circuit and the rectifying device comprising a plurality of coils arranged to form two secondary circuits that are traversed respectively by currents of uniform direction, and a magnetizable core for the coils adapted to provide a leakage path for fluxes between the coils pertaining respectively to the two secondary circuits.
10. The combination with an alternating current circuit, and a current-rectifying device, of a transformer interposed between the circuit and the rectifying device comprising a plurality of coils arranged to form two secondary circuits that are traversed respectively by currents of uniform direction, and a magnetizable core for the coils adapted to provide leakage paths for fluxes surrounding the coils pertaining respectively to the two secondary circuits, the said paths

having a common portion in which the leakage fluxes are of uniform direction.

11. The combination with an alternating current circuit, and a current-rectifying device, of a transformer interposed between the circuit and the rectifying device comprising a plurality of coils arranged to form two secondary circuits that are traversed respectively by currents of uniform direction, and means providing a low reluctance leakage path between the coils pertaining respectively to the two secondary circuits.

12. A transformer comprising a plurality of secondary coils and low reluctance leakage paths between the said coils.

In witness whereof I have hereunto set my hand this 22nd day of May, 1905.

CHARLES P. STEINMETZ.
